UNITED STATES PATENT OFFICE.

HENRY ADAMS, OF STAMFORD, CONNECTICUT.

CENTRIFUGAL PULVERIZER.

1,221,952.

Specification of Letters Patent. Patented Apr. 10, 1917.

Application filed April 6, 1914, Serial No. 829,938. Renewed October 21, 1916. Serial No. 127,033.

To all whom it may concern:

Be it known that I, HENRY ADAMS, a citizen of the United States, residing at Stamford, in the county of Fairfield and State of Connecticut, have invented certain new and useful Improvements in Centrifugal Pulverizers; and I do declare the following to be a full, clear, and exact description of the invention, such as will enable others skilled in the art to which it appertains to make and use the same.

My invention relates to improvements in centrifugal pulverizers and has for its primary object to provide a device of this character which may be simply and inexpensively constructed and which will effectually perform the functions for which it is designed.

In carrying out the above end, I provide a pair of vertically spaced tables having coacting grinding surfaces on their contiguous faces, means for rotating one or both of said tables and means whereby the upper table is rigidly braced against vibration and yet allowed to freely rotate.

A secondary object of the invention is to construct the above mentioned grinding or pulverizing surfaces in such a manner as to cause the material, being pulverized, to be moved outwardly by centrifugal force and to be effectually pulverized on its outward course.

Still another object of the invention is to construct the bracing means for the upper table in the most simple manner consistent with the proper operation of the device.

A still further object is to construct the entire machine of as few parts as possible and to so construct the individual parts as to render them readily attachable or detachable for the purpose of repairing, and the like.

With the above objects in view, the invention resides in certain novel features of construction and combination herein described and claimed and shown in the drawings wherein:—

Figure 1 is a vertical section of my improved pulverizing machine;

Fig. 2 is a horizontal section thereof, taken on the plane of the line 2—2 of Fig. 1;

Fig. 3 is a detail elevation of a portion of one of the grinding rings, showing the manner in which the same may be corrugated.

In the accompanying drawings, I have illustrated my invention as comprising in

general, an upper table 1, a lower table 2 spaced therefrom, coacting pulverizing rings 3 and 4 carried respectively by the tables 1 and 2, supporting and bracing legs 5 for the upper table, means for feeding the material, to be treated to the lower table and means whereby either or both of said tables may be rotated.

The upper table 1 is preferably of circular formation and is constructed of a solid metal plate having a pair of upwardly and inwardly inclining openings 6 through which tubes 7 pass and enter the lower end of a pan 8 which revolves with a shaft 9 to which the table 1 is rigidly keyed. Thus it will be seen that any material fed to the pan 8, by a pipe 10 or other suitable means, will descend through the tubes 7 and will be discharged upon the lower table 2.

As above suggested, the table 1 is provided with supporting and bracing legs 5, said legs being here shown as inclining downwardly and outwardly from the periphery of said table and carrying anti-friction rollers 11 on their lower ends, said rollers running upon an annular track 12. By the provision of the legs 5 and their mounting, it will be seen that the table 1 is rigidly braced against tilting, the expediency of this provision becoming apparent as the specification proceeds.

The pulverizing rings 3 are here shown as being concentrically arranged and of right angle triangular shape in cross section, their hypotenuses 13 inclining upwardly and outwardly while their altitudes 14 are disposed in vertical planes. The inclined and vertical surfaces 13 and 14 coact with similar surfaces 13' and 14' which are formed by constructing the rings 4 in the same manner as the rings 3 with the exception that the hypotenuses of said rings 4 incline downwardly and inwardly from their altitudes while the hypotenuses of the rings 3, as above stated, incline outwardly and upwardly from their altitudes.

By reference more particularly to Fig. 1, it will be seen that the rings 3 and 4 intermesh when the parts are properly arranged and that said rings are rendered readily detachable by means of bolts 15.

As will be hereinafter more clearly set forth, the table 2 rotates at a greater speed than the table 1 and in fact, the table 1 need not be rotated at all when pulverizing certain materials. I have illustrated table 2

as comprising a circular metal top 16 which is of less thickness than the table 1 and is provided with a central hub 17 from which bracing ribs 18 radiate, said ribs serving to 5 impart the necessary rigidity to the table 2.

For the purpose of rigidly and revolvably supporting the table 2, I provide an upright bearing shaft 19 which is rigidly keyed within the hub 17, depends therefrom and 10 is revolvably mounted in a rigid bearing 20, a pulley 21 being provided for the purpose of transmitting power to said shaft from a source not shown.

With the parts as above described, the 15 operation of the invention is as follows: The material, to be pulverized, is fed through the pipe 10 and into the pan 8 from which it is discharged through the tubes 7, onto the innermost ring 4 of the table 2, 20 which table is now being swiftly rotated. The rotation of said table 2 will cause the material deposited thereon to be thrown outwardly by centrifugal force. On its outward movement, said material rides successively up the inclined surfaces 13' of the 25 rings 4 and falls upon the next inclined surface. The surfaces 13 and 13' and 14 and 14' now coact to cause the numerous particles of the material to contact with each other, a 30 rolling motion being imparted to said particles which effectually pulverizes the same.

As the material nears the outer edge of the table 2, the centrifugal force is of course increased and the pulverizing action is also 35 increased, thus completely pulverizing the material by the time it leaves the table 2.

For the purpose of receiving the material, discharged from said table 2, I provide a rigidly supported trough or launder 22 40 which is disposed below the edge of said table while the discharged material is directed into said launder by means of a depending skirt 23 which is carried by the table 1.

If found desirable, the upper table 1 may 45 be rotated by means of a suitable pulley 24 to which power may be applied. When said table 1 is being revolved it becomes necessary to impart reverse movements to said 50 tables 1 and 2. It is during the rotary movement of the table 1, that the rollers 11 and track 12 come into action.

In Fig. 3, I have illustrated a portion of a pulverizing ring 3' which is similar in con-

struction to the rings 3 and 4 with the exception that its active face is corrugated as indicated at 3''. This form of ring operates in connection with the remaining features of the machine in the same manner as the rings 5 and 4 and it is thought that its construction and operation as well as the construction and operation of the various other features of the invention, will be readily understood without requiring a more extended explanation.

I have described my invention with considerable minuteness but I do not wish to be limited to details of construction, proportioning of parts or other minor features other than those amplified in the appended 60 claims.

Having thus particularly described my invention, what I desire to obtain by Letters-Patent is:—

1. A centrifugal pulverizer comprising a 75 pair of rotatably mounted vertically spaced tables provided on their opposed faces with laterally spaced concentric annular detachably mounted grinding elements in the form of ribs triangular in cross section, those on 80 one table being arranged opposite the spaces between those on the other, means for feeding material to the lower table, and means for rotating said tables.

2. In a centrifugal pulverizer, the combination with a support and an annular track thereon; of a table mounted for rotation on said support, an additional table spaced above the aforesaid table and having outwardly inclined legs thereon, rollers on the 90 lower ends of said legs and received on said track to rotatably support the last mentioned table thereon, the inner opposed faces of said tables having annular concentric grinding ribs removably secured thereto, 95 said ribs being triangular in cross section and those on one table being arranged opposite the spaces between those on the other, means for feeding material to the lower table and means for rotating said tables. 100

In testimony whereof I have hereunto set my hand in presence of two subscribing witnesses.

HENRY ADAMS.
